Attorney

UNITED STATES PATENT OFFICE.

HENRY ALTERGOTT, OF SHEBOYGAN, WISCONSIN.

ATTACHABLE BAND BRAKE.

1,417,880.

Specification of Letters Patent. Patented May 30, 1922.

Application filed October 1, 1920. Serial No. 414,004.

To all whom it may concern:

Be it known that I, HENRY ALTERGOTT, a citizen of the United States, residing at Sheboygan, in the county of Sheboygan and 5 State of Wisconsin, have invented certain new and useful Improvements in Attachable Band Brakes, of which the following is a specification.

The invention has for an object to effect 10 an improvement in brakes for motor vehicles, and particularly to provide an attachable brake assembly adapted to be mounted upon motor vehicles of a familiar type now upon the market. It is a particular object 15 to enable the mounting of this brake without requiring machine operations of any kind, or alterations in structure of the familiar type of vehicle as now constructed, in order to enable the mounting of the band brake to 20 coact with the drum already upon the vehicle and to be operated by the brake rod now employed for operating an expanding internal brake operating upon the drum, upon which same drum my device will engage. 25 The invention is also readily adaptable in a similar manner to various other vehicles, as will be readily understood.

Additional objects, advantages and features of invention will appear from the construction and arrangement, as well as combination of parts hereinafter described and shown in the drawings, wherein

Figure 1 is an inner side elevation of the right hand brake assembly,

Fig. 2 is a rear elevation thereof,

Fig. 3 is a fragmentary sectional view thereof,

Fig. 4 is a detail of the brake perch.

In the particular type of vehicle upon 40 which the present embodiment of my invention is shown, the rear axle assembly includes a housing with outer tubular elements 10, upon which are brazed or otherwise secured terminal castings 11, which include 45 planiform circular brake housing plates 12, one of which castings is here shown. The plate 12 is braced at the upper part by integral diagonal and parallel web elements 13, between which there is formed a boss 14 50 through which an opening is drilled, which receives the threaded shank 15 of a spring perch 16 from which the shackles 17 are hung to carry the rear spring 18 as shown in Fig. 2. The plate 12 is also provided 55 with a boss 19 at the rear side, in which a bolt 20 is customarily engaged, suitably

formed to support a brake shoe not illustrated, and customarily located at the outer side of the plate 12. A brake drum 21, secured to the rear wheel 22, is customarily 60 employed, of a diameter the same as that of the plate 12.

My invention includes the formation of a 65 brake perch 25, which is shown approximately one-half full size in Fig. 4. This perch includes a base plate 26 of considerable body, shaped so as to snugly fit against the plate 12 between the webs 13, this plate 26 being recessed on the outer side to fit snugly over the boss 14 and a web 14' extending 70 therebelow, as indicated at 27 in Fig. 4. The inner face of the plate 26 is smoothly finished, and centrally of the circular upper part of the recess 27 there is formed an opening 28 adapted to aline with 75 the opening through the boss 14, and receive commonly therewith the shank 15 of the spring perch. The plate 26 is formed with an outwardly projecting shoulder portion 29 at its upper part, adapted to rest 80 upon the upper edge of the plate 12 so that the weight carried by the perch 16 when engaged in the plate 26 will be transmitted to the plate 12 without undue strain upon the shank 15.

A horizontal rectilinear arm 30 is projected outwardly from an upward extension 31 upon the upper part of the plate 26, this arm being rectangular in cross section, its lower side being located so as to lie above 85 the plate 12 and the drum 21 a distance greater than the thickness of the brake band and its lining, to be subsequently described. In the upper side of the arm 30 there is formed a recess 32 in which there is 90 set a spring 33 confined between the bottom of the recess and the upper side of the rectangular passage 34 formed in a suspension lug 35 welded or integrally formed upon a resilient brake band 36 the ends of which 100 are located forwardly of the assembly. A set screw 34' is engaged perpendicularly in the member 35, being entered axially in the spring 33, and if desired may be used to limit downward movement of the upper 105 part of the band with respect to the arm 30, the passage 34 being considerably larger vertically than the arm 30. A lock nut 37 is engaged upon the screw 34' to hold it in 110 adjusted position. With the screw slightly entered in the passage 34, the spring engages therewith and being snugly seated in the

recess 32 serves to hold the brake band snugly against lateral movement, and also against rattling, and when the brake is applied and greater strain may be expected 5 tending to move the band laterally with respect to the drum 21, the downward movement of the upper part of the band due to its tightening upon the drum will enter the lower part of the screw 34' into the compacted spring 33 and the recess 32, thereby 10 making positive the securement of the upper part of the band against lateral displacement. At the rear part of the band there is firmly fixed therein or thereon a stud 39, 15 and an L-shaped bracket piece 40 is provided, having a short arm and a long arm, the former being transversely curved to fit snugly against the outer side of the band 36, and formed with a transverse slot 40' engaged 20 around the stud 39, whereby the latter may have a certain play therein transversely of the arm. A compression spring 41 is confined between the bracket 40 and the outer end of the stud, between washers 42, one 25 against the bracket and the other held upon the stud by a cotter pin 42' inserted through the outer end of the stud. The long arm of the bracket is formed with a longitudinal slot 43, adapted to receive the usual brake 30 mounting bolt 20 before mentioned. The bracket 40 is adjusted so as to normally hold the band away from the drum by support of the spring 41, and when the brake is tightened, the spring will be compressed, permitting 35 the band to move inwardly against the drum, as will be readily understood. On one end of the band, there is provided a pivot ear 44, the band being provided with a thickened portion 45 as a suitable support 40 for the ear and to prevent inturning of the band end, the thickened portion extending away from the ear a distance, tapering gradually to the standard thickness of the major 45 part of the band, as indicated at 46, so that liability of flexure of the band over a limited area is minimized. A fulcrum lug 47 is formed upon the opposite end of the band, similarly supported by a thickened portion 48, extended a suitable distance and 50 tapered as in the case of the thickened portion 45. The lug 47 is formed with an opening therethrough receiving loosely a fulcrum bolt 49 pivoted upon a lever 50 of the second class, a short arm of which is pivoted upon 55 the lug 44, the long arm of which is extended upwardly so as to lie closely beside the bolt 49 when the brake is in released position. A brake rod 52 is engaged with the outer end of the arm 51 in the usual manner by means 60 of a nut and lock nut as at 53, the fulcrum bolt is adjustable to compensate for the wear of the lining 54 of the band 36.

The passage 34 is slightly greater in width horizontally than the horizontal 65 transverse dimension of the arm 30, so that

when it is necessary to adjust the bracket 40 the band hanger 35 may rock when necessary, upon the arm 30, so that when the brake is released, there will be no strain upon the band between the two mountings. 70

It is important to note that at the base of the hanger 35, the body thereof is extended outwardly, tapering gradually, until the standard thickness of the band 36 is attained, as indicated at 55 so that localization 75 of flexure of the band and strain, is avoided, and liability of fracture minimized. The same is true of the tapering of the thickened portions 45 and 48 at the ends of the bands, as will be readily appreciated. 80

The entire band is resiliently supported and held against rattling by the character of mounting provided, in addition to the other advantages indicated.

In the installation of my device, the regular brake equipment ordinarily installed upon vehicles of this type may be dispensed with, or retained as an auxiliary. The mounting bolt 20 of the regular brake is removed and engaged through the mounting 85 bracket 40, and my brake perch 25 is secured in place by securing the regular spring perch 16 thereupon as illustrated in Fig. 3, the removal of the wheel being involved in such installation. Before replacement of 90 the wheel, the band is put in place by having the hanger 35 engaged upon the arm 30 and the stud 39 inserted through the bracket 40. The band being then adjusted suitably with respect to the periphery of the plate 95 12, the wheel may be readily removed and replaced without interference by the band 36 or its lining. The fulcrum bolt 49 is adjusted so that the end portions of the band 100 will lie clear of the drum when the brake is 105 in released position.

In use, the forward movement of the brake rod 52 will draw downwardly upon the bolt 49 and cause the lever 50 to bear upwardly on the lower end portion 45 of the 110 band 36. This causes a contraction of the band upon the drum 21. The arm 30 prevents rotation of the band with the drum, and holds the part 35 against rotating movement with respect to the perch 25. Consequently, the contracting of the band produces longitudinal movement in the end portions of the band. The spring 41, normally serving to hold the rear part of the band spaced from the drum yields and permits 115 the contraction of the band, the slot 40' accommodating whatever longitudinal movement of the band stud 39 there may be at this point. The band is also preferably made with sufficient stress tending to open 120 it, to hold the end portions 45 and 48 away from the drum when the brake is released. Adjustment for wear may be made by means of the nuts engaged upon the bolt 49 over 125 the lug 47. 130

What is claimed:

1. The combination with an element fixed with respect to an axle of a perch element attachable thereto and having a lateral arm 5 for disposition adjacent a brake drum, a band element mounted for limited vertical movement on said arm, means yieldingly supporting the band normally above its operative position, a mounting engaged 10 with the band at a distance from said perch element including means constructed for movement of the band toward and away from a circumscribed drum and for longitudinal movement of the band on the said 15 mounting and resilient means directly but yieldingly opposing movement of the band toward the drum at said mounting.
  2. A band brake comprising an upper mounting including a lateral arm, a band 20 having a hanger element thereon formed
- with a transverse passage to receive said arm for relative vertical and rocking movement of the two, said arm being recessed on its upper side, a spring snugly engaged in the recess and confined between the arm and 25 upper side of said passage for yielding support of the band, an element projected axially into the spring from the hanger, a lower support for the band including an L-shaped bracket having a transversely 30 slotted short arm and a longitudinally slotted long arm, a stud on the band slidable longitudinally of the first slot and stud, a spring confined between the end of the stud and short arm, a mounting bolt adjustable 35 in the slot of the long arm and releasable means to contract the band.

In testimony whereof I have affixed my signature.

HENRY ALTERGOTT.
